SPEED CONTROL DEVICE FOR MACHINES

Louis Hermitte, Paris, France, assignor to Société Rateau, La Courneuve Seine, France, a corporate body of France

Application August 9, 1938, Serial No. 223,938
In France August 13, 1937

4 Claims. (Cl. 264—7)

The present invention relates to devices for automatically controlling the speed of revolution of a prime mover.

The object of the present invention is to provide a device for effecting this controlling action in accordance with variations of the speed of another rotary machine.

According to the essential feature of the present invention, both the primary mover to be controlled and said other machine are each associated with a volumetric pump (that is to say a pump the rate of delivery of which is proportional to its speed of revolution), which they drive at speeds depending upon the speed of said prime mover and the speed of said other machine, respectively, according to predetermined relationships. The resistance of the discharge circuit of the pump associated with the prime mover is controlled in accordance with the discharge pressure of the other pump, and, in turn, the discharge pressure of said first mentioned pump controls the speed of revolution of said prime mover.

Other features of the present invention will result from the following detailed description of a specific embodiment thereof.

A preferred embodiment of the present invention will be hereinafter described, with reference to the accompanying drawing, given merely by way of example, and in which:

The only figure is a diagrammatical view of a plant made according to an embodiment of the present invention.

As shown by the drawing 1 is a steam turbine which drives a utilization apparatus 2 of any kind whatsoever. It also drives, at the same, or a proportional speed, a tachometric pump 3 of the volumetric type, that is to say, the rate of delivery of which is proportional to its speed of revolution. The pump 3 draws oil, or any other liquid, from a tank 4, through a pipe 5 and delivers it through a pipe 6, into the chamber 7 of a valve body 23, which communicates with a discharge chamber 8, by way of a passage 9 between a profiled valve 10 and its seat 24. The oil which has passed into the discharge chamber 8 then returns to the tank 4 by way of a pipe 11.

Steam is supplied to the turbine 1 by a pipe 12 and passes through a throttle valve 44, which is controlled by a pressure regulator which will now be described:

This pressure regulator includes a cylinder 40 in which is mounted a piston 41, urged upwardly by a spring 14. The chamber 42 above this piston communicates with an intermediate point

of the delivery pipe 6 of the volumetric pump 3 through a pipe 15. Piston 41 carries a rod 43 provided, at its end, with a valve 44. This valve 44 cooperates with a seat 45 which divides the valve body 46 into two chambers 13 and 17, the first of which communicates directly with the steam supply pipe 12, while the other communicates directly with the inlet of the turbine 1.

This pressure regulator, which is of conventional type, has its valve 44 designed in such manner that it maintains a uniform pressure in the pipe 6, for instance in the following manner, corresponding to the example illustrated by the drawing:

When the pressure in the pipe 6 tends to drop, piston 41 is moved upwardly by its spring 14 and valve 44 opens the passage between chambers 14 and 37 to a larger area so that the feed of steam to the turbine 1 is increased, thus tending to accelerate the speed of said turbine in such manner as to compensate for the drop of pressure in pipe 6. Similarly, a rise of the pressure in said pipe 6 produces a movement of valve 44 in the opposite direction and reduces the feed of steam to the turbine.

On the other hand, the pressure in the pipe 6 depends solely on the rate of flow of the liquid through the passage 9. Consequently, for a given cross-sectional area of said passage, the pressure in said pipe 6 depends entirely on the delivery by the tachometric pump 3, that is to say, on the rotational speed of the engine. Therefore, the device according to the invention also maintains a constant rotational speed of the turbine 1, so long as the cross-sectional area of the passage 9 remains unchanged.

If the cross-sectional area of said passage 9 is modified, the speed of the plant will be automatically varied until a new value is attained in respect of which the velocity of the liquid in the passage 9, and the delivery pressure of the pump once more attain their predetermined regulating value.

Thus, the speed of the turbine 1 depends upon the area of the passage 9, and therefore upon the position of the rod 32 (which carries the valve 10 cooperating with seat 24 for determining this passage). I will now explain how the position of this rod 32 is controlled by the speed of the other machine 27.

The machine 27 in accordance with the speed N_2 of which it is desired to control the speed N_1 of the prime mover 1, also drives a tachometric pump 28, the return circuit of which includes a pipe 29, the chamber 36 of a valve body 26, a

passage 39 existing between a valve 30 and a corresponding seat 20 of said valve body, the second chamber 37 of this valve body, and a pipe 31 leading back to the tank.

5 The valves 10 and 30 are both mounted on the rod 32 itself rigidly carried by a piston 33 co-operating with a cylinder 25. The chamber 22 existing in said cylinder 25 under this piston 33 communicates, through the pipe 34, with the pipe 29. The other face of the piston 33 is subjected to a counteracting spring 35.

The pressure in the pipe 29 depends on the delivery of the pump 28 (i. e. on the speed N_2 of the machine 21) and on the cross-sectional area 15 of the passage 39 existing between the valve 30 and its seat 20.

On the other hand, this pressure should balance the stress of the spring 35. Therefore, starting, for instance, from a predetermined state 20 of equilibrium, if the speed N_2 increases, the pressure in the pipe 29 will rise and compress the spring 35, thus lifting the valve 30 and increasing the cross-sectional area of the passage 39 defined by that valve.

25 A new state of equilibrium is established for a slightly higher position of the valve 30. It will be evident, therefore, that, to each value of the speed N_2 , there will correspond a given position of rod 32, and of valve 10. Thus, according to 30 the profile given to the valve 10, a relation can be established between the speed N_2 and the cross-sectional area of the passage 9 defined by said valve.

According to the foregoing, therefore, the speed 35 N_1 of the prime mover 1 can, automatically, be made dependent on the speed N_2 of the machine 21, in accordance with a predetermined relationship, by suitably designing the profile of the valve 10.

40 In order fully to explain the utility of my device, I will give an example of an application thereof, to wit to the regulation of the combustion in a furnace.

This application corresponds to the case of a 45 furnace fed with liquid fuel by means of a volumetric pump driven by machine 21 (and distinct from volumetric pump 28).

It will be supposed that the air necessary for the combustion of this fuel is fed by a blower or 50 equivalent machine which is the utilization machine 2 driven by the turbine 1.

The feed of the fuel to the furnace is substantially proportional to the speed of revolution of the machine 21.

55 The feed of air supplied by the blower 2 depends, with a predetermined relationship, upon the speed of revolution of the turbine 1, this relationship being determined by the working characteristics of this blower and the resistance of the circuit into which it feeds air.

60 Variations of the operating conditions of the furnace are obtained by varying the speed of the machine 21, so as to feed a variable amount of fuel to the burners.

65 The result to be obtained is the automatic adaptation of the amount of air supplied by the blower 2 in such manner that, whatever be the feed of liquid fuel, the feed of combustion air sent to the furnace corresponds to the best possible conditions of combustion.

70 This condition corresponds to a predetermined relationship between the feed of fuel and the feed of air, that is to say to a predetermined relationship of the speed of the turbine 1 and of the other machine 21.

The device an example of which has been above described permits of obtaining automatically this predetermined relationship, whatever it may be, and whether it is a simple law of proportionality or a more complicated law.

75 In the example above described, the machine 21 may be, for instance, an electric motor, a steam turbine, etc.

Also, it should be well understood that the prime mover 1 is not necessarily a steam turbine. It may consist of any machine the speed of revolution of which is controlled by the position of the piston 41 of the pressure responsive regulator.

Likewise, while, in the above example of application of my invention, I suppose that the 15 furnace was fed with liquid fuel, it is clear that the invention applies as well to the case of a furnace with a movable grid for feeding coal. In this case, motor 21, instead of driving a fuel pump, would drive a continuous movement grid for the 20 coal, and the device would ensure a predetermined relationship between the feed of the grid and the working of the blower.

In a general manner, while I have, in the above description, disclosed what I deem to be practical and efficient embodiments of the present invention, it should be well understood that I do not wish to be limited thereto, as there might be changes made in the arrangement, disposition, and form of the parts without departing 30 from the principle of the present invention as comprehended within the scope of the appended claims.

What I claim is:

1. In a plant including a machine and a motor, 35 a device for regulating the speed of said motor in accordance with the speed of said machine, which comprises, in combination, a volumetric pump driven by said machine at a speed proportional to the speed thereof, a volumetric pump 40 driven by said motor at a speed proportional to the speed thereof, a discharge circuit for said second mentioned pump, means, operative by variations of the delivery pressure of said first mentioned pump, for varying the resistance of 45 said discharge circuit to the flow of fluid therethrough, according to a predetermined law of correspondence between the delivery pressure of the first mentioned pump and the resistance of 50 said discharge circuit and means, responsive to variations of the delivery pressure of said second mentioned pump, for controlling the speed of said motor.

2. In a plant including a machine and a motor, 55 a device for regulating the speed of said motor in accordance with the speed of said machine, which comprises, in combination, a volumetric pump driven by said machine at a speed proportional to the speed thereof, a volumetric pump 60 driven by said motor at a speed proportional to the speed thereof, a discharge circuit for said second mentioned pump, a valve in said discharge circuit for more or less throttling said circuit according to a predetermined law as a function 65 of the displacement of said valve, means, operative by variations of said first pump delivery pressure, for displacing said valve, and means, responsive to variations of the delivery pressure of 70 said second pump, for controlling the speed of said motor.

3. In a plant including a machine and a motor, 75 a device for regulating the speed of said motor in accordance with the speed of said machine, which comprises, in combination, a volumetric pump driven by said machine at a speed propor- 80

tional to the speed thereof, a discharge circuit for said pump, a volumetric pump driven by said motor at a speed proportional to the speed thereof, a discharge circuit for said second mentioned pump, a valve in each of said discharge circuits respectively for more or less throttling it, a rod common to both of said valves for rigidly interconnecting them, means, operative by variations of the delivery pressure of said first mentioned pump, for controlling said two valves, and means, responsive to variations of the delivery pressure of said second mentioned pump, for controlling the speed of said motor.

4. In a plant including a machine and a motor, a device for regulating the speed of said motor in accordance with the speed of said machine, which comprises, in combination, a volumetric

pump driven by said machine at a speed proportional to the speed thereof, a discharge circuit for said pump, a volumetric pump driven by said motor at a speed proportional to the speed thereof, a discharge circuit for said second mentioned pump, a valve in each of said discharge circuits for more or less throttling it, a rod common to both of said valves for rigidly interconnecting them, a stationary cylinder, a spring loaded piston in said cylinder, a passage transmitting the delivery pressure of said first mentioned pump to one side of said piston in said cylinder means for rigidly coupling said piston with said rod, and means, responsive to variations of the delivery pressure of said second mentioned pump, for controlling the speed of said motor.

LOUIS HERMITTE.
